UNITED STATES PATENT OFFICE.

NICHOLAS L. GULLIFORD, OF PEABODY, MASSACHUSETTS, ASSIGNOR TO GREGORY & READ COMPANY, OF BOSTON, MASSACHUSETTS, A CORPORATION OF MASSACHUSETTS.

SHOE-SHAPING MACHINE.

Application filed August 2, 1923. Serial No. 655,180.

My invention relates to machines for shaping the soles of boots and shoes and particularly to a new machine for operating upon or beveling the heel portion of an outer sole to give to the same the proper shape to receive upon it the heel of the boot or shoe.

In the manufacture of boots and shoes of certain classes, especially women's shoes having wooden heels, it has heretofore been customary to make the heels with a concaved top so that the marginal portion of said top would seat against the shoe thus avoiding openings or cracks between the heel and shoe. It has also been customary, and in most cases desirable or necessary, to bevel the marginal portion of the outer side of the heel portion of the outer sole to give to it the proper convex shape to fit into the concaved top of the heel, thereby ensuring contact of the outer edge of the concaved top side of the heel with the upper just outside of the edge of the sole of the boot or shoe to hide the heel portion of the outer sole. This beveling of the marginal part of the heel portion of the sole to prepare it for the reception of the heel has never heretofore been successfully performed, so far as I am aware, except manually by means of a knife in the hands of a skilled workman, and the chief object of my invention is to provide a new cutting machine for use in shaping the marginal portions of the soles of boots and shoes.

To this and other ends my invention consists of a machine of the character described having the peculiar features of construction and mode of operation hereinafter more fully set forth, the novel features of my invention being particularly pointed out and defined in the claims at the close of the specification.

Other features of my invention are also hereinafter set forth.

In the accompanying drawings:

Figure 1 is a plan view of a sole shaping machine embodying my invention.

Figure 2 is a side elevation of the machine shown in Fig. 1, part of the jack mechanism being shown as broken away and in section.

Figure 3 is a plan view of the work rest hereinafter referred to.

Figures 4 and 5 are details illustrating the construction and operation of the cutter hereinafter described.

Figure 6 is a front elevation of the jack mechanism hereinafter referred to.

Figure 7 is a section on line 7—7 of Fig. 6 with the last shown in Fig. 6 removed.

Figure 8 is a plan view of the jack mechanism shown in Fig. 6.

Figure 9 is a perspective view of the heel portion of a shoe showing the manner in which the present machine bevels the marginal portion of the heel end of the sole.

Figure 10 is a plan view of a boot or shoe showing the condition of the sole after having been operated upon by the present machine.

Figure 11 is a side elevation of a low shoe showing a heel in position upon the same after the heel end of the sole has been shaped by my new machine.

The embodiment of my invention herein shown includes a frame comprising a base 1 adapted to be fastened by screws 2 to a bench 3 or other support. Upon this base 1 is fastened an arm or bracket 4 that is forked at its upper outer end and provided with bearings 5 supporting a cutter shaft 6.

This cutter shaft 6 has fast upon one end thereof a pulley 7 through which said shaft is driven by means of a belt, not shown. Upon the opposite end of shaft 6 is fixed a cutter 8 consisting, preferably, of a wheel of peculiar construction and mode of operation in that it is provided with cutting edges 9 and 9' upon its opposite faces, respectively, that are disposed crosswise of the axis of said wheel 8. These cutting edges 9 and 9' join the ends of peripheral cutting edges 10 that are disposed lengthwise of said axis but preferably obliquely with relation thereto.

Beneath and closely adjacent the cutter 8 is a work rest comprising a sole supporting and upper shielding member 12 and a sole positioning abutment member 13, both carried by a bracket 14 fastened by means of a screw 15 to a downward extension of the bed piece 1, said screw extending through a slot 16 formed in bracket 14 to permit of adjustment of the bracket and parts carried thereby toward and from the cutter. The bracket 14 rests upon a screw 17 on base 1 which affords means for raising and lowering the bracket and co-operates with screw 15 in holding the same rigidly in adjusted position.

The sole positioning abutment 13 is a bar slidably mounted in ways 18 upon the top side of bracket 14, said ways being parallel with the plane of the cutter 8. Upon its top side the abutment member 13 is made

with ways 19, also parallel with said plane, in which the sole supporting member 12 is slidably mounted with its top side tangent to the circular path of the outer ends of the 5 teeth 11 of cutter 8, or substantially so, as shown in Fig. 4. The two members 12 and 13 are rigidly fastened together and to the bracket 14 by means of a bolt 20 and nut 21, said bolt extending through a hole 22 10 in the bracket 14 and through slots 23 and 24 formed through the members 12 and 13, respectively.

At their inner rear ends the members 12 and 13 are engaged respectively, by screws 15 25 and 26 by means of which said members may be accurately adjusted relatively and positioned relatively to cutter 8 when bolt 20 is loosened, said screws being rotatably mounted upon the bracket 14 and held 20 against endwise movement with relation thereto.

The shoe that is to be operated upon, shown at S and mounted upon a last, is presented sidewise to the workrest 12-13 25 with the front work engaging end or nose 12' of member 12 occupying a position between the marginal portion of the sole and the upper, and with said upper resting against the outer end of abutment 13, all as 30 shown in Fig. 4 in full lines and indicated by dotted lines in Fig. 2.

The work engaging nose 12' of member 12 is more or less wedge-shaped in vertical 35 longitudinal section so that when the shoe is forced back against the abutment 13 it crowds the marginal portion of the sole upwardly across the path of the blades 11 which in rotating cut away the marginal portion of the outer side of the sole upon a 40 bevel as illustrated in Figs. 4, 9 and 10. It will be understood, of course, that the middle portion of the heel of the outer sole is nailed or otherwise fastened to the shoe as usual so that only the marginal portion of 45 the sole is lifted into the path of the cutter and operated upon by the latter.

During the cutting operation relative movement is effected between the cutter and sole in a direction to cause the cutter to 50 traverse the marginal part of the heel of the sole from the breast at one side thereof around the heel end of the sole to the breast at the opposite side, the sole sliding across the top of the nose 12' as this movement 55 proceeds. During this operation, also, the shoe is held against the abutment 13 which serves to determine the width of the bevel produced by the cutter, and its position with 60 relation to the original outline or edge of the heel of the sole.

The shoe may, if desired, be wholly supported and guided by the hands of the operator during the cutting operation, or the machine may, as herein shown, be provided 65 with jack mechanism for supporting and

guiding the shoe while it is being operated upon by the cutter 8.

The shoe supporting and guiding jack mechanism herein shown consists of a jack comprising a table 27 pivotally mounted 70 upon a pintle 28 that is supported by a forked arm or bracket 29 fastened to bracket 14. Table 27 has a flat top upon which is slidably mounted a carriage 30 whose base portion 31 is part circular as shown, said 75 part-circular portion bearing against an up-standing flange 32 provided at the rear side of table 27 and parallel with the axis of cutter 8. Upon its under side the carriage 30 is made with a T-slot 33 closed at each 80 end and within which is arranged a T-shaped block 34. Block 34 is rotatably connected with table 27 by a stud bolt 35 whose center or axis is positioned the same distance away from flange 32 as the radius of 85 the part-circular portion 31 of carriage 30. Sliding movement of carriage 30 relatively to table 27 and block 34 is limited in one direction by the end 36 of slot 33 and in the other direction by an adjustable stop 37, 90 herein shown as a screw mounted on carriage 30 and provided with a check nut 38.

The carriage 30 is made with a vertical or upwardly extending tapped hole 39, Fig. 95 7, to receive the threaded shank of a vertically adjustable post 40, said post being secured in adjusted position by means of a check nut 41. The upper end portion of this post is adapted to freely enter the socket of an ordinary last L and is made with an annular flange 42 which serves as a supporting seat for said last. Post 40 is positioned so as to support the last with the curved rear end portion 43 at the back of 100 the heel of the sole, Fig. 10, substantially or approximately concentric with a perpendicular z-z, Fig. 6, passing through the center of the part-circular portion 31 of the carriage 30. In other words the post 40 105 positions the last so that the curved back part 43 of the heel of the sole is concentric with the part circular portion 31. A toe rest 44 mounted on carriage 30 supports the forward end of the last with its median line v-v, Fig. 10, canted or obliquely disposed with relation to the axis of cutter 8 so as to position the median line w-w of 110 the heel of the sole and last parallel with said axis.

The toe rest 44 is made with a round stem or shank 45 mounted in an arm projecting from carriage 30 and fastened therein by a set screw 46. This provides for rotative adjustment of toe rest 44 to the extent of 180 degrees to adapt the jack to right or left 115 shoes and lasts.

The adjustable stop screw 37 is provided to adapt the jack mechanism to heels of different lengths.

The axis of stud bolt 35 is in a plane, indi-

cated by line $x-x$, Fig. 6, parallel with the sides or faces of cutter 8 and passing through the middle of the latter, the stop screw 37 being set so that when in engagement with one side of block 34, the distance between the opposite side of said block and the end 36 of T-slot 33 is the same as the distance between lines $z-z$ and $x-x$, said distance corresponding with the distance between the center of the curved back 43 of the heel and a transverse line at the breast of the heel.

When the last L with the shoe upon it occupies the full line position a shown in Fig. 6, and the shoe is brought into engagement with the work rest as in Fig. 4, it will be clear that the cutter 8 will form the breast end of the bevel s' , Fig. 9, at one side of the shank, and that if carriage 30 is slid on table 27 in the direction of the arrow a' , Fig. 6, to the limit of its movement in that direction into position b while the cutter is rotating and engaging the sole, said cutter will form the bevel along one side of the heel and the line $z-z$ will then coincide with the line $x-x$, the latter line being the axis of bolt 35. The carriage 30 can now be swung 180 degrees on bolt 35 in a contra-clockwise direction, Fig. 1, so as to shift the last from position b to position c , during which time, or movement, the cutter forms the bevel s' around the back 43 of the heel. From position c the carriage 30 is then slid on table 27 in the direction of the arrow c' into position d where it is stopped by the engagement of stop screw 37 with block 34. During this latter movement of the carriage from position c to position d cutter 8 forms the bevel along the opposite side of the heel as far as the breast. As will be clear, the cutting edges 9 and 9' produce clean-cut and abrupt perpendicular shoulders s^2 , Fig. 10, at the opposite ends of the bevel s' to fit against the breast of the wooden heel H, Fig. 11.

There are many different styles of heels, some having breasts which are straight across and others having breasts which are concaved. Some, also, have breasts which are oblique. When shaping soles to receive heels of the first kind the cutting operation is started and finished with the plane of the cutter perpendicular to the median line $w-w$, Fig. 10, of the heel, and when shaping soles to receive heels of the second and third kinds the cutting operation should be started and finished with the cutter 8 disposed obliquely with relation to said median line.

In order to ensure this proper relationship between the cutter and sole at the start and completion of the cutting operation I provide positioning gauges 47 and 48 at opposite sides, Figs. 6 and 8, of stud bolt 35, the gauge 47 serving, by engagement with the

outside ball of the sole, when the shoe occupies position a , to position the sole properly with relation to the cutter at the start of the cutting operation, and the gauge 48 serving by engagement with the inside ball of the sole, when the latter occupies position c , to position said sole with relation to the cutter as the cutting operation is completed. These gauges 47 and 48 are fixed, by means of screws 49, to the table 27 so that they may be adjusted toward and from carriage 30 to vary the angular relationship between the shoulders s^2 , Figs. 9 and 10, and the median line $w-w$ according to the style of heel that is to be applied to the sole.

When the cutting operation has been completed the jack mechanism is swung outwardly on the pintle 28 into a position where the table 27 rests upon lugs 50, 50 projecting from the arms of bracket 29, to permit of the removal of the last L and substitution of another.

What I claim is:

1. A machine of the character described comprising a cutter that is continuously rotated in one direction provided with side cutting edges and a transverse end cutting edge; means for supporting and positioning a shoe sole while being operated upon by the cutter to form a bevel along the margin thereof, and means for limiting the movement of the shoe sole with relation to the cutter to confine the latter to the heel portion of the sole.

2. A machine of the character described comprising a cutter that is continuously rotated in one direction provided with cutting edges upon the opposite sides thereof and with a transverse cutting edge at the end thereof; means for operating said cutter; means for supporting and positioning a shoe sole while being operated upon by said cutter to form a bevel along the margin thereof, and means for limiting the movement of the shoe sole with relation to the cutter to confine the cutting operations of the latter to the heel seat of the sole.

3. A machine of the character described comprising a cutter movable on an axis and provided upon each side thereof with an approximately radial cutting edge that is disposed crosswise of said axis and with two outer cutting edges disposed lengthwise of said axis, each oppositely oblique with relation to the other and both traveling paths between said approximately radial side edges with the forward end of one of said oblique outer edges at the path of the outer end of the approximately radial edge at one side of said cutter and the forward end of the other oblique outer cutting edge at the path of the outer end of the approximately radial edge at the opposite side of said cutter, and means for supporting a shoe sole while being operated upon by said cutter.

4. In a machine of the character described, the combination with a cutter constructed in accordance with claim 3, of a work rest comprising a sole supporting and positioning member engaging the crease at the side of the shoe between the marginal part of the sole and the upper to support said marginal part of the sole obliquely in the path of said cutting edges, and means for operating said cutter. 65
5. A machine of the character described having, in combination, a cutter constructed in accordance with claim 3; a work rest comprising a sole supporting and positioning member engaging the crease at the side of the shoe between the marginal part of the sole and the upper to support said marginal part of the sole in the path of said cutting edges, and an abutment engaging the side of the shoe to control the width of the bevel produced by the cutter. 70
- 10 6. A machine of the character described comprising a rotating cutter provided upon each side thereof with approximately radial cutting edges that are disposed crosswise of the axis of the cutter and with peripheral cutting edges between the planes of the approximately radial cutting edges and disposed lengthwise of said axis, alternate 75
- 15 30 peripheral cutting edges being obliquely disposed in one direction with relation to said axis and the other peripheral cutting edges being obliquely disposed in the opposite direction with relation to said axis, and means 80 for supporting and positioning the sole of a shoe while it is being operated upon by said cutter. 85
- 20 7. A machine of the character described comprising a rotatable cutter; a sole supporting and positioning member to occupy the crease at the side of a shoe between the outer sole and upper so as to support the marginal part of the sole and present the same obliquely to the cutter, and means for supporting 90
- 25 40 45 the shoe in co-operative relation with said member with provision for movement in a direction lengthwise of the axis of said cutter and rotatively. 100
- 30 50 55 60 65 70 75 80 85 90 95 100 105 110 115 120 125
8. A machine of the character described comprising a rotatable cutter; a sole supporting and positioning member to occupy the crease at the side of a shoe between the outer sole and upper so as to support the marginal part of a sole and present the same obliquely to the cutter; means for supporting the shoe in co-operative relative with said member with provision for movement in a direction lengthwise of the axis of said cutter and rotatively, and means for limiting the movement of the shoe lengthwise of the axis of the cutter to confine the operations of the latter to the heel portion of the sole. 125
9. A machine of the character described constructed in accordance with claim 7 and having also means for limiting the rotative movement of said shoe. 65
10. A machine of the character described constructed in accordance with claim 7 and having also means for limiting the movement of the shoe lengthwise of the axis of the cutter to confine the operations of the latter to the heel portion of the sole, with provision for adjustment to adapt the machine to operate upon heel seats of various lengths. 70
11. A machine of the character described constructed in accordance with claim 7 and having also means for limiting the rotative movement of the shoe so that the cutter occupies a definite angular position with relation to the median line of the heel seat when in position at the breast end of the latter. 80
12. A machine of the character described constructed in accordance with claim 7 and having also means for limiting the rotative movement of the shoe so that the cutter occupies a definite angular position with relation to the median line of the heel seat when in position at the breast end of the latter, said last mentioned means having provision for adjustment to vary this angular relationship to accord with the style of heel to be applied to the sole. 85
13. In a machine of the character described, the combination of a rotatable cutter; a sole supporting member between which and said cutter the marginal portion of a sole is passed, said member occupying the crease at the side of a shoe between the outer sole and upper so as to support the marginal part of the sole against the trust of the cutter and present the same obliquely to the cutter, and an abutment engaging the upper of the shoe to position the latter relatively to the cutter. 95
14. A machine of the character described, constructed in accordance with claim 13 wherein said member and abutment are relatively adjustable to vary the width of bevel produced by the cutter. 100
15. A machine of the character described comprising a cutter movable about an axis and having approximately radial cutting side edges disposed crosswise of said axis and an outer edge disposed lengthwise of said axis but obliquely with relation thereto, and means for supporting a shoe sole adjacent said cutter with its marginal portion extending obliquely across the path of the edges of said cutter and with provision for movement of said sole and cutter relatively in a direction to cause the cutter to traverse the marginal portion of the sole and bevel the same. 115
- In testimony whereof I have affixed my signature. 125

NICHOLAS L. GULLIFORD.
